UNITED STATES PATENT OFFICE.

HATTIE McCAW, OF WALLA WALLA, WASHINGTON.

SCISSORS.

Application filed November 19, 1921. Serial No. 516,371.

To all whom it may concern:

Be it known that I, HATTIE McCaw, a citizen of the United States, residing at Walla Walla, in the county of Walla Walla and State of Washington, have invented 5 new and useful Improvements in Scissors, of which the following is a specification.

This invention relates to improvements in scissors and has for its primary object to 10 furnish the shanks of the scissors with detachable blades.

Another object of this invention is to provide means, whereby the blades may be retained within the shanks and yet quickly 15 and easily be detached therefrom, when occasion may demand.

A further object of this invention is to equip the scissors with blades offering two reversible cutting edges.

20 Other objects and advantages will be apparent during the course of the following description.

In the accompanying drawings forming a part of this specification, and in which like 25 numerals are employed to designate like parts throughout the same,

Fig. 1 is a front elevation of a pair of scissors constructed in accordance with my invention.

30 Fig. 2 is a perspective view of one of the blades detached from the shank of the scissors and also showing in perspective the retaining means for said blade,

Fig. 3 is a top plan view of a portion of 35 one of the shanks with the blade retained therein,

Fig. 4 is a transverse vertical section through the shank taken on the line 4—4 of Figure 3,

40 Fig. 5 is a vertical section through the same taken on a line 5—5 of Figure 3, and

Fig. 6 is a cross section through the scissors, showing the position of the cutting edges the view being taken on the line 6—6 45 of Figure 1.

In the accompanying drawings wherein for the purpose of illustration is shown a preferred embodiment of my invention, the numerals 7 and 8 designate the shanks of 50 the scissors which terminate in handles 9, the said shanks being either detachably or permanently connected together by a fastening element 10.

Provided in each of the shanks is an 55 angular recess 11 adapted to receive therein a blade 12 having two cutting edges 13 and

14. Each of the blades is tapered toward one end and conforms to the shape of its shank, while adjacent the opposite end of each blade I have provided a pair of opposed notches 15 with the end of the blade terminating in a reduced head, as indicated by the numeral 16.

In order that each blade may be retained in its respective recess, so that there will be 60 no danger of the blade being accidentally displaced from its shank, I have secured to each of the shanks, by means of a set screw 17, a spring clip 18, which terminates at one end in a depending lip 19. Headless screws 20 65 also penetrate the shanks 7 and 8 and are receivable in the blades, as shown to advantage in Figure 6. These screws assure the retention of the blades within the shanks until it is desired to release the blades there- 70 from.

From this construction it will be apparent that the blades can readily be detachable from the shanks when it is desired to either 75 present new cutting edges or to insert an 80 entirely new blade. This detaching operation can be readily performed by swinging the clip 18 from the set screw 17, which serves as a pivotal point. Furthermore, by the use of the detachable blades, angularly 85 disposed in the shanks, as shown to advantage in Figure 6, efficient cutting edges will be presented. By virtue of the reversible features of the blades great economy 90 will be obtained for this type of scissors as 95 compared to the usual type wherein a frequent re-sharpening of permanent blades is necessary.

It is to be understood that the form of 100 my invention, herewith shown and described 95 is to be taken as a preferred example of the same, and that various changes in the shape, size and arrangement of parts may be resorted to without departing from the spirit of the invention or the scope of the sub- 100 joined claims.

Having thus described my invention, I claim:—

1. A pair of scissors comprising a pair of pivotally connected shanks provided with 105 recesses therein, blades in the recesses of said shanks, each blade being reversible and having two cutting edges, and means for detachably retaining each of said blades in its shank, said means comprising spring clips 110 each secured at one end to each shank and terminating at the opposite end in a depend-

ing lip adapted to contact with the shanks
blade.

2. A pair of scissors comprising a pair of
pivotally connected shanks having angularly
5 disposed recesses therein, blades positioned
in the recesses of said shanks, said blades
being reversible and having two cutting
edges and conforming to the shape of the
shanks, each of said blades having a pair of

opposed notches adjacent one end thereof, 10
and spring clips each secured at one end to
each shank and terminating at its opposite
end in a depending lip adapted to be re-
ceived in the exposed notch of said blade.

In testimony whereof I affix my signa- 15
ture.

MRS. HATTIE McCAW.
